UNITED STATES PATENT OFFICE.

PETER H. COLLING, OF ALBANY, NEW YORK.

COAL HOD.

1,413,518.

Specification of Letters Patent. Patented Apr. 18, 1922.

Application filed March 7, 1921. Serial No. 450,388.

To all whom it may concern:

Be it known that I, PETER H. COLLING, a citizen of the United States, residing at Albany, in the county of Albany and State 5 of New York, have invented certain new and useful Improvements in Coal Hods; and I do hereby declare the following to be a full, clear, and exact description of the invention, such as will enable others skilled in the art to 10 which it appertains to make and use the same.

The invention relates to household utensils designed chiefly for carrying coal, kindling, ashes and refuse generally, such as sweepings, garbage and trash.

The invention provides a receptacle embodying relatively upper and lower compartments, each compartment being readily accessible for supplying or removing material 20 therefrom as required without any interference of one with the other.

The invention furthermore consists of a receptacle of the character aforesaid having a tray adjunctive to the lower compartment 25 and projecting outwardly from the body of the receptacle for convenience of receiving kindling and other material not readily receivable in the lower compartment.

Other objects and advantages will be apparent and suggest themselves as the nature 30 of the invention is understood.

While the drawings illustrate an embodiment of the invention, it is to be understood that in adapting the same to meet different 35 conditions and requirements, various changes in the form, proportion and minor details of construction may be resorted to without departing from the nature of the invention.

Referring to the accompanying drawings 40 forming a part of the specification,

Figure 1 is a vertical central longitudinal section of a coal hod illustrative of the invention,

Figure 2 is a horizontal section taken on 45 the line 2—2 of Figure 1, and

Figure 3 is a detail view of the blank from which the tray is formed, the parts being foldable on the dotted lines.

Corresponding and like parts are referred 50 to in the following description and designated in the several views of the drawings by like reference characters.

The numeral 1 designates the body of the coal hod, utensil or other receptacle, which

is modified in accordance with the present 55 invention to provide an upper compartment 2 and a lower compartment 3. The utensil or receptacle 1 is provided with the usual base or stand 4. A portion is cut from the side of the body 1 to provide an opening 5 disposed preferably in the rear and opposite the lower compartment 3. The bottom of the upper compartment 2 is designated by the numeral 6 and is located a short distance above the opening 5. The bottom 60 of the lower compartment 3 is designated by the numeral 7 and corresponds with the usual bottom of the hod or utensil. It will thus be understood that the compartments 2 and 3 are separate and independent. Access 70 to the upper compartment 2 is had through the top of the body 1. The lower compartment 3 is accessible through the opening 5. A tray 8 is disposed opposite the opening 5 about in line with the bottom 7 thereof. The 75 bottom of the tray 8 is preferably in the same plane as the bottom 7 and may be jointed thereto in any manner. The sides of the tray 8 slope upwardly towards their inner ends and are made fast to the sides of the body 1 at the ends of the opening 5 in any manner commonly practiced in the sheet metal art. The upper edge of the sides of the tray is reinforced and strengthened 80 in substantially the same manner as the upper edge of the body 1. The tray is formed from a blank substantially as illustrated in Figure 3, the same having approximately parallel extensions 9 in line with side portions and which are inwardly curved and secured at their ends with their lower edges made fast to the bottom portion of the tray.

The parts, when assembled, may be secured by spot welding, riveting or in any manner usually resorted to in the art of 95 sheet metal working so as to provide a substantial structure and enable the work to be effected in a rapid and economical way. The invention provides a coal hod, utensil or similar receptacle, having independent compartments and an offstanding tray, thus coal may be placed in the upper compartment and kindling in the lower compartment, or the upper compartment may receive ashes and the lower compartment 100 sweepings and other refuse while the tray may be utilized as a receptacle for garbage or other waste matter. It is observed that 105

the tray 8 is in line with the spout of the hod or utensil and extends in an opposite direction thereto. This enables the weight to be more uniformly balanced on the carrying bail or handle 10.

In the event of the outer portion of the tray 8 being overbalanced by heavy sticks of wood or other material tending to tilt the hod 1 and discharge the contents of the tray, each end of the bail 10 is formed with an arm 11 having a lateral extension 12 adapted to engage the upper edge of the hod when the bail is in vertical position, thereby preventing backward tilting of the hod and downward tipping of the tray.

What is claimed is:

1. A coal hod, or analogous utensil, having a spout and embodying independent upper and lower compartments separated by a fixed partition, and having an opening in the rear side of the lower compartment opposite the said spout and in line with the bottom, and a tray in line with said opening and projecting rearwardly from the utensil in an opposite direction to the spout and comprising a bottom and sides, the latter extending along opposite sides of the said

opening and attached to the sides of the utensil at the ends of the opening.

2. A coal hod embodying upper and lower compartments and having an opening in its lower rear portion, the bottom of the upper compartment being some distance above the top of said opening, and a tray projecting from the hod in an opposite direction to the spout thereof and in line with the opening formed in a side thereof, said tray being formed from a single blank embodying a bottom and sides, the latter including extensions, and the sides sloping upwardly and inwardly and attached to the body of the hod adjacent the ends of the opening formed in a side thereof, and the bottom of the tray being substantially in the same horizontal plane with the bottom of the hod which likewise constitutes the bottom of the lower compartment.

In testimony whereof I affix my signature in presence of two witnesses.

PETER H. COLLING.

Witnesses:

AUGUST N. COLLING,
ARCHIBALD WARHURST.
